CARBURETOR

Irving Steinhardt, New York, N. Y.

Application February 12, 1932, Serial No. 592,493

9 Claims. (Cl. 261—49)

This invention relates to an improvement in a carburetor for explosive engines, the present invention being in the nature of an improvement upon the arrangement shown and described in my Patent No. 1,888,248, issued Nov. 22nd, 1932.

In engines used for driving automobiles and the like it is a known fact that when the automobile is travelling at good speed along a level highway the explosive mixture furnished by the carburetor may advantageously be considerably leaner than when the engine is operating at slower speeds or when driving the vehicle up an incline, also that where the carburetor of the engine feeds its gasoline into the air blast through an aperture of a given size the resultant mixture of air and gas is relatively leaner at low speeds than at higher speeds.

It is an object of the present invention therefore to provide improved simple, practical and efficient means for causing the mixture to be automatically made leaner in proportion to increasing speed of the engine.

A further object is to provide improved means for temporarily enriching the mixture delivered by the carburetor whenever the throttle is moved toward open position.

A further object is to so construct the carburetor as to perform the above objects without necessity for the use of any mechanically operated governors or the like connected with the engine shaft.

A further and more detailed object is to so construct the carburetor that it will include an air intake valve and connections between said valve and the mixture controlling needle valve whereby the effects of said needle valve will be modified at different engine speeds by action of said air valve.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawing which is to be taken as a part of this specification, and in which I have shown merely a preferred form of embodiment of the invention:—

Fig. 1 is a diagrammatic view of a carburetor device embodying this invention and showing the same in operative association with an explosive engine; and

Fig. 2 is a fragmentary detail view taken at

right angles to the view Fig. 1 and showing the relationship of parts of the valve control illustrated in Fig. 1.

Referring to the drawing for describing in detail the exemplary structure illustrated therein, the reference character L indicates the intake manifold of an ordinary explosive engine G.

The carburetor, indicated generally by the reference character H, includes the usual gasoline reservoir 1 containing the float 2 for keeping the gasoline level constant. The jet 3 is arranged within the Venturi tube 4 which communicates with the passage 5 within which is arranged the throttle valve 6.

Gasoline enters the reservoir 1 through a tube 7, and a supply of air enters through a pipe 8 which communicates with the bottom end of the Venturi tube.

The usual operating rod 9 is connected with the throttle valve, as by means of the radial arm 10 fixed to the shaft of said valve for manually controlling the movements of the throttle valve in the customary way.

Whenever the throttle valve 6 is rotated open to admit a larger volume of explosive mixture into the cylinders for accelerating the speed of the engine the increased speed of the pistons causes the blast of air surging around the jet 3 within the Venturi tube to be increased in velocity thereby tearing off from the jet relatively more gasoline, proportionate to the volume of air passing in a given period, than was torn off at the lower speed at which the engine had been previously running.

The increase in proportion of gasoline to air would continue to grow greater progressively unless means be provided to prevent it.

To this end the present invention proposes the use of a gasoline needle 11 or other suitable means arranged for controlling the amount of gasoline which may pass out of the jet 3 under differing conditions. For convenience of illustration the needle or valve 11 is here shown to be mounted to move vertically within a tube 12 at the bottom of which is formed a seat 13 with which the valve 11 co-operates to control movement of gasoline into the jet 3. The needle or valve 11 is longitudinally vertically movable within the tube 12 and extending upwardly therefrom is a small rod or link 14 with which it is connected to the throttle valve 6 at one side of the pivot shaft of said valve as at 15 so that opening movement of the throttle valve will lift the rod 14 and the valve 11.

The connection between the rod 14 and the valve 11 is of a yielding character such as to

normally hold the valve and rod in one position but to permit movement of the valve and rod independently of each other upon occasion. As a simple expedient to this end the valve is shown 5 to be hollow with the rod 14 extending downwardly into its hollow interior and having a compression coil spring 16 interengaging between the rod and the valve within the valve. The upper end of the spring bears against the top wall 17 10 of the valve while its lower end bears against a head 18 which is provided at the lower end of the rod.

At one side of the valve 11 is an air valve 19 controlling an air inlet opening 20. This valve 15 is shown as being carried upon a rod 21 and as being spring pressed to closed position by a suitable compression coil spring 22 arranged within the body of the carburetor. The opening 20 communicates with the opening 5 for the purpose of 20 supplying fresh air to said opening 5 to mingle with the mixture admitted through the Venturi tube when the engine is turning over at high speeds.

Mounted upon a pivot 23 is a horizontal bar 24 25 which traverses the top of the valve 11 and extends into pivotal connection as at 25 with the valve rod 21.

The pivot 23 is formed upon a slide collar 26 30 movable longitudinally of the bar 24 and is carried at the free end of an arm 27 which is pivoted as at 28 upon the body of the carburetor, said arm being adjustable upon said pivot 28 so as to adjust the pivot 23 longitudinally along the bar 24 as may be necessary to produce the best results 35 in different engines, as will be readily understood.

Where the bar 24 traverses the valve 11 the valve is formed with a suitable shoulder or other appropriate means as 29 for engagement with the bar.

40 The operation of this mechanism is as follows: When the throttle valve is operated toward open position the rod 14, actuating through the spring 16, will lift the valve 11 away from the seat 13 so that gasoline will flow freely to the 45 jet 3. The speed of the engine will depend upon the amount to which the valve 6 has been turned, and the position of valve 19 will depend upon the speed of the engine. The suction felt within the passage 5 will force the valve 19 open more 50 and more as the speed increases.

It follows therefore that the valve 11, having been lifted to a certain point by movement of the throttle valve, will be moved down again somewhat by engagement of the rod 24 with the 55 shoulder 29 of the valve 11 as the speed of the engine increases, until the supply of gasoline to the jet 3 is so limited as to affect the engine speed. If the valve 6 be further moved to increase the speed under these conditions, the spring 16 will 60 add its power to the spring 22 and thus increase the resistance to opening movement of the valve 19. A proper explosive mixture is thus insured for movement past the valve 6 at all speeds.

As many changes could be made in this construction without departing from the scope of the invention as defined in the following claims, it is intended that all matter contained in the above description, or shown in the accompanying drawing, shall be interpreted as illustrative only and 70 not in a limiting sense.

Having thus described my invention, what I claim as new and desired to secure by Letters Patent is:—

75 1. A carburetor comprising an air passage, a gasoline jet within said air passage, a throttle

valve, a control member for determining the gasoline discharge at said gasoline jet, and means including an automatically operating air inlet valve and connections whereby increase in the speed of the engine and the consequent increase 5 in the volume and velocity of air past the automatic air inlet valve will move said control member to cause a reduction in the gasoline discharge at said gasoline jet.

2. A carburetor comprising an air passage, a 10 gasoline jet within said air passage, a throttle valve, a control member for determining the gasoline discharge at said gasoline jet, and means including an automatically operating air inlet 15 valve and connections whereby to move the control member to cause a reduction in the gasoline discharge at said gasoline jet in response to an opening movement of the throttle valve and the resultant increase in the volume and velocity of 20 air passing the automatic air valve.

3. A carburetor comprising an air passage, a gasoline jet within said air passage, a throttle valve, a control member for determining the gasoline discharge at said gasoline jet, an air valve automatically to feed air through the carburetor in varying quantities dependent upon the speed of the engine, and connections between the throttle valve, the air valve and the control member to move the control member to cause a reduction in the gasoline discharge at said gasoline jet in response to an opening movement of the throttle valve and an opening movement of the air valve.

4. A carburetor comprising an air passage, a gasoline jet within said air passage, a throttle 35 valve, a control member for determining the gasoline discharge at said gasoline jet, connecting means between the throttle valve and the control member by which to move the control member by movement of the throttle valve, said connecting means including a pull rod extending between the control member and the throttle valve and being resiliently extensible to permit movement of the control member independent of movement of the throttle valve, and means automatically operable to move the control member toward closed position independently of movement of the throttle valve and in an amount dependent upon the speed of the engine.

5. A carburetor comprising an air passage, a gasoline jet within said air passage, a throttle valve, a control member for determining the gasoline discharge at said gasoline jet, connecting means between the throttle valve and the control member by which to move the control member by movement of the throttle valve, said connecting means being resilient to permit movement of the control member independent of movement of the throttle valve, and means to move the control member independently of movement of the throttle valve and to an amount dependent upon the speed of the engine, said last means including an automatic air valve and a member connected with said air valve arranged to press the control member in one direction as 50 said air valve moves open.

6. A carburetor comprising an air passage, a gasoline jet within said air passage, a throttle valve, a control member for determining the gasoline discharge at said gasoline jet, connecting means between the throttle valve and the control member by which to move the control member by movement of the throttle valve, said connecting means being resilient to permit movement of the control member independent of 70 movement of the control member.

- movement of the throttle valve, and means to move the control member independently of movement of the throttle valve and to an amount dependent upon the speed of the engine, said last means including an automatic air valve, a pivotally mounted bar extending from its point of support into connection with said air valve and having an intermediate part arranged to engage said control member to press the control member in one direction as said air valve moves open.

7. A carburetor comprising an air passage, a gasoline jet within said air passage, a throttle valve, a control member for determining the gasoline discharge at said gasoline jet, connecting means between the throttle valve and the control member by which to move the control member by movement of the throttle valve, said connecting means being resilient to permit movement of the control member independent of movement of the throttle valve, and means to move the control member independently of movement of the throttle valve and to an amount dependent upon the speed of the engine, said last means including an automatic air valve, a pivotally mounted bar extending from its point of support into connection with said air valve and having an intermediate part arranged to engage said control member to press the control member in one direction as said air valve moves open, together with means by which to shift the pivot support of said bar along the length thereof for thereby adjusting the extent of pressure applied to the control member for a given amount of movement of said air valve.

9. A carburetor comprising an air passage, a gasoline jet within said air passage, a throttle valve, a control member for determining the gasoline discharge at said gasoline jet, connecting means between the throttle valve and the control member by which to move the control member by movement of the throttle valve, said connecting means being resilient to permit movement of the control member independent of movement of the throttle valve, and means to move the control member independently of movement of the throttle valve and to an amount dependent upon the speed of the engine, said last means including an automatic air valve and a member connected with said air valve arranged to press the control member in one direction as said air valve moves open, together with means by which to adjust the extent of pressure applied to the control member for a given amount of movement of said air valve.

8. A carburetor comprising an air passage, a gasoline jet within said air passage, a throttle valve, a control member for determining the gasoline discharge at said gasoline jet, connecting means between the throttle valve and the control member by which to move the control member in one direction as said air valve moves open, together with means by which to adjust the extent of pressure applied to the control member for a given amount of movement of said air valve.
